INFUSION SET

Kenneth Raines, Bethlehem, Pa., assignor to Burron
Medical Products, Inc., Bethlehem, Pa.

Continuation-in-part of design applications Ser. No.
22,700, Apr. 29, 1970, Ser. No. 22,710, Apr. 29,
1970, Ser. No. 22,711, Apr. 29, 1970, and Ser. No.
22,712, Apr. 29, 1970. This application Nov. 19,
1970, Ser. No. 26,078

Term of patent 14 years

Int. Cl. D24—02

U.S. Cl. D83—12

FIG. 1.

FIG. 2.

FIG. 26

FIG. 1 is a perspective view from the side and top of the infusion set, showing my new design;

FIG. 2 is a front view from the cannula end of the infusion set;

FIG. 3 is a side elevation of the infusion set in folded position;

FIG. 4 is a front view of FIG. 3;

FIG. 5 is a perspective view from the side and top of a modified infusion set, showing my new design;

FIG. 6 is a top plan view;

FIG. 7 is a front view from the cannula end;

FIG. 8 is a side view of FIG. 6;

FIG. 9 is a perspective view of the infusion set with the wings in elevated position;

FIG. 10 is a side elevation of FIG. 9;

FIG. 11 is a top plan view of FIG. 9;

FIG. 12 is a perspective view of an additional modified infusion set, showing my new design;

FIG. 13 is a top plan view;

FIG. 14 is a front view from the cannula end of the infusion set;

FIG. 15 is a side elevation of FIG. 13;

FIG. 16 is a perspective view of the infusion set, with the wings in elevated position;

FIG. 17 is a side view of FIG. 16;

FIG. 18 is a top plan view of FIG. 16;

FIG. 19 is a perspective view from the top and side of a modified infusion set, showing my new design;

FIG. 20 is a top plan view;

FIG. 21 is a side elevation of FIG. 20;

FIG. 22 is a front view from the cannula end;

FIG. 23 is a perspective view of the infusion set, with the wings in vertical position;

FIG. 24 is a side plan view of FIG. 23;

FIG. 25 is a rear elevation of FIG. 23; and

FIG. 26 is a top plan view of FIG. 23.

This is a continuation-in-part of design applications Ser. Nos. D. 22,700, D. 22,710, D. 22,711 and D. 22,712, filed Apr. 29, 1970 and now abandoned.

I claim:

The ornamental design for an infusion set, as shown and described.
